COMPOSITE BUSHING

Frank E. Rice, Detroit, Mich., assignor, by mesne assignments, to American Tap Bush Company, Detroit, Mich., a corporation of Delaware

Application May 29, 1933, Serial No. 673,499

9 Claims. (Cl. 16—2)

The present invention relates to composite bushings and has to do more particularly with tap bushes so constructed as to be readily applicable to steel barrels.

5 An object of the present invention is to provide improved tap bushes for steel barrels.

A further object of the present invention is to provide a composite tap bush which may be welded in place in a metal barrel or keg and 10 which is formed of two members which are intimately connected together to provide a unitary structure, one of the members possessing such metallurgical characteristics which permit welding it to a metal barrel or keg.

15 The above, other and further objects of the invention will be apparent from the following description, accompanying drawing, and appended claims.

One embodiment of the invention contemplates 20 the provision of a preformed steel shell, preferably of stainless steel or any soft steel, in which a cast metal switch is cast and with which said switch becomes intimately and permanently connected. The shell is utilized as part of the mold 25 for the cast metal switch.

The accompanying drawing illustrates a composite bushing embodying principles of the present invention, and the views thereof are as follows:

30 Figure 1 is a side elevational view, partially in section, of a tap applied to a composite bushing, of the present invention, which bushing in turn is secured in a steel barrel, a fragmental portion only of the steel barrel being shown.

35 Figure 2 is a top plan view of the upper or outer face of the composite bushing of Figure 1.

Figure 3 is a sectional view taken substantially in the plane of line III—III of Figure 1.

The drawing will now be explained.

40 A fragmental portion of a double shell steel barrel is illustrated in Figure 1 with the outer shell designated as 1 and the inner shell as 2.

A composite bushing is inserted in a bunghole, designated at A, in Figure 1, with the opening in 45 the outer shell 1 of greater size than the opening in the inner shell 2.

The composite bushing there illustrated consists of a shell or outer member 3, which is preferably of stainless steel, and preformed to provide the ultimate shape desired and the switch or inner part, designated generally at B.

The shell 3 is dished to provide an annular attaching flange 4, a centrally disposed upstanding collar or tube portion 5 and a recessed body.

55 Formed in the interior of the shell are grooves

or indentations 6 and 7 into which flows the molten metal for forming the cast metal switch B, thus providing interlock between the shell 3 and the switch B.

The shell 3 serves as a mold or pattern for the exterior of the switch B and becomes intimately associated with the switch B in permanent relationship, by reason of the fact that the switch B is cast in the shell 3 as a mold.

In casting the switch B, suitable cores are 10 utilized so as to form an upstanding sleeve or neck 8 about the upstanding tube 5 of the shell 3. The upper end of the sleeve 8 is provided with an outwardly directed cam flange 9, provided at diametrically opposite points with 15 notches 10 for receiving the inturned lugs 11 of a tap, designated generally at C. The outer face of the flange 9 is preferably spherical in section for a purpose to be later explained. The switch B is so cast as to provide an outwardly extending 20 annual flange 4a overlying the flange 4 of the shell 3.

The composite bushing is applied to the outer shell 1 prior to the installation of the inner shell 2. The composite bushing is secured to the shells 25 1 and 2 by welding, as indicated at 12.

The tap C is provided with the usual connector ring or thimble 13 which is provided with the inturned lugs 11 for cooperating with the flanges 9 of the switch. The thimble 13 is removably 30 connected to the body of the tap C by a threaded ring 14 which is freely rotatable on the body and arranged for threaded engagement with the thimble 13, in the usual manner.

The inner end of the body of the tap C is inclined or upwardly divergently, so as to dish the washer 15 as the thimble 13 is tightened in hooking engagement with the flanges 9 of the switch, for effecting the gastight joint between the tap C and the interior of the barrel.

The switch B is designed to correspond in size and shape with the switches now in use in wooden kegs or barrels so that the taps now on hand may be readily applied to steel barrels equipped with switches of the present invention.

The tap C is applied to a composite bushing of the present invention, by applying it with its inturned lugs overlying the notches 10 in the sleeve of the switch B whereupon the tap is lowered and turned until the lugs 11 strike stops 45 16 formed as integral parts of the casting of the switch B.

The shell 3, as before stated, is made preferably of stainless steel so as not to be affected by the barrel contents, such as beer. The provision of 50 55

the shell 3 surrounding the cast metal switch B enables ready application of the composite bushing to steel barrels as there are thus provided sufficient surfaces of proper material and of suitable fusible characteristics for welding purposes.

The tap C, of Figure 1, is illustrated as partially turned in its application to the switch B. When fully turned into operative position, the flange 17, of the connector ring or thimble 13, 10 will bear against the flange 11 of the switch B.

It is commercially desirable to make that portion of a tap bush, which interlocks with a tap, of cast metal. In applying tap bushes to steel barrels, it was found that a bush made 15 wholly of cast metal, could not be readily and economically welded to the steel barrel. This is because of several dissimilar characteristics present in the cast metal of the bush and the low carbon content of the steel utilized for making 20 the barrel bodies.

The grain structure and composition of cast metal and soft metal are quite dissimilar, likewise the melting points are different so that welding of these metals of dissimilar characteristics is very impractical. The variation of the melting point of these two metals seriously hinders the fusing of the welding metal and furthermore is almost impossible to obtain a proper flux for properly welding the cast metal to the 30 soft metal of the barrel body.

Another characteristic of cast iron, which makes it difficult to weld to mild steel, is the extremely high coefficient of expansion of the cast iron.

35 The present invention enables the use of a composite bushing for welding to steel barrels, wherein a shell of mild steel is provided for welding or fusing to the barrel body, and which carries an inner part of cast iron forming the 40 necessary flanges and notches for cooperation with a tap for interlocking the tap to the bush.

The invention has been described herein more or less precisely as to details, yet it is to be understood that the invention is not to be limited 45 thereby, as changes may be made in the arrangement and proportions of parts and equivalents may be substituted, without departing from the spirit and scope of the invention.

The invention is claimed as follows:

50 1. A composite tap bush for a steel barrel comprising a shell of stainless steel adapted to be welded in an opening in the barrel, a tap attaching cast metal switch disposed within and completely covering the interior of said shell, 55 and said shell and said switch having interfitting projections and recesses for preventing relative rotation of said shell and switch.

2. A composite tap bush for a steel barrel comprising a dished metal switch having an outwardly turned annular flange and a central upstanding sleeve or neck for a pump rod, the outer end of said sleeve having an outwardly projecting flange with spaced notches in it for receiving the lugs of a tap connector, a shell of stainless 65 steel surrounding the exterior of said switch and extending within said neck, said shell having parts adapted to be welded in an opening in a steel barrel for securing said switch in said barrel, and said shell and said switch having interengageable projections and recesses for interlocking the same against relative rotation.

3. A composite tap bush for a steel barrel comprising an outer or shell part of mild steel having substantially the same fusible characteristics as the barrel, and an inner part or switch

providing the usual cam flange for receiving a tap in connected relation, interengaging projections and recesses on said parts permanently connecting the parts together against relative rotation.

4. A composite tap bush for a steel barrel comprising a shell or outer part of sheet metal recessed or dished to provide a body with an exterior annular attaching flange and a central upstanding tube for receiving a pump rod, an inner part or switch in said shell and conforming generally to the interior of said shell and surrounding said tube providing a neck and having adjacent the upper end of said neck the usual cam flange for receiving a tap in connected relation, and the upper end of said tube being flared over the upper end of said neck to connect together said shell and inner part in permanent relation and to prevent relative movement between said inner part and said shell, and said inner and outer parts having interengageable portions for preventing relative movement of said parts.

5. A composite tap bush for a steel barrel, said bush being formed of wrought and cast metal 25 so constructed as to present a portion of the wrought metal for welding to a steel barrel; said bush comprising an outer dished shell of low carbon steel, such as stainless steel, and an inner part of cast metal to provide the usual 30 flanges for receiving a tap in connected relation; said outer shell having portions adapted to be welded in a bush opening in a steel barrel whereby parts of the bush of substantially the same fusible characteristics as said barrel are 35 presented for welding to the barrel, and said shell and inner part having cooperating projections and recesses for preventing relative rotation between them.

6. A composite tap bush for a steel barrel, said bush comprising an inner part or switch and an outer part of substantially the same fusible characteristics as the steel barrel, said inner part being fashioned to provide the usual flanges and notches for receiving a tap in connected relation, 45 and said inner and outer parts having cooperating projections and recesses for preventing relative rotation of said parts.

7. In equipment for a container, a member comprising an annular bottom and inner and outer side walls, a second member fitting said inner wall and provided around its upper end with oppositely related outwardly extending flanges forming notches between their ends and ribs extending longitudinally of said second member and disposed in diametrical relation and each remote from one of said notches, the end portion of the inner wall extending over into engagement with said second member to secure it in position and interlocking means for preventing rotation of said 60 second member relative to said first member.

8. In equipment for a container, a member comprising an annular bottom and inner and outer side walls, a second member fitting said inner wall and provided around its upper end with oppositely related outwardly extending flanges forming notches between their ends and ribs extending longitudinally of said second member and disposed in diametrical relation and each remote from one of said notches, the end portion of the inner wall extending over into engagement with said second member to secure it in position and interlocking means between the lower end of said second member and said first member for preventing rotation of said 70 75

second member relative to said first member, said means comprising spaced recesses formed in the metal wall of one of said parts and spaced pins carried by the other part and extending into 5 said recesses.

9. A composite tap bush for a steel barrel comprising an outer part of steel adapted to be

welded in an opening in a barrel, a switch disposed within said outer part, and said outer part and switch having interfitting projections and recesses for preventing relative rotative movement between them and cooperating to produce a 5 unitary structure.

FRANK E. RICE,
